[57] CLAIM

The ornamental design for a water closet, as shown and described.

DESCRIPTION

FIG. 1 is a left, top, frontal perspective view of a water closet embodying our new design;

FIG. 2 is a top plan view thereof;

FIG. 3 is a left side elevational view thereof, the right side elevational view being the mirror image of the left side shown;

FIG. 4 is a front elevational view thereof;

FIG. 5 is a rear elevational view thereof; and,

FIG. 6 is a bottom plan view thereof.

The fragmentary broken line representations of holes in FIGS. 1 and 2 are for the purpose of illustration only and form no part of the claimed design.
